UNITED STATES PATENT OFFICE.

THOMAS SCULLY, OF NEW YORK, N. Y.

ELECTRICAL INSULATOR.

1,216,000.

Specification of Letters Patent. Patented Feb. 13, 1917.

Application filed March 26, 1915. Serial No. 15,697.

To all whom it may concern:

Be it known that I, THOMAS SCULLY, a citizen of the United States, and a resident of New York, in the county of New York and State of New York, have invented certain new and useful Improvements in Electrical Insulators, of which the following is a specification.

The invention relates to electrical insulators for high or low voltages and more particularly to so-called strain insulators, that is to say, insulators in which the material is held under compression by two looped conductors whose loops are interlinked but spaced apart by means of the insulator to avoid contact with each other, the said loops being usually held in planes at right angles to each other to secure the maximum spacing.

20 The invention has for its object to provide an insulator of this type which shall be mechanically strong, though small enough at high voltages for commercial purposes, and be readily constructed and at not too great an expense.

A further object of the invention is to provide an insulator in which the creepage surface is equal in all directions between the respective conductors and which insulator is so constructed, furthermore, that it will readily shed rain and moisture and prevent the same from settling or collecting thereon notwithstanding any position which the insulator may assume.

35 In the accompanying drawings which illustrate the invention—

Figure 1 illustrates the improved insulator in perspective.

Fig. 2 is a front elevation thereof, and

Fig. 3 is a top view.

Fig. 4 is an end elevation.

Fig. 5 illustrates, in perspective, a modification.

Fig. 6 is a front elevation thereof, and

Fig. 7 an end view.

Similar characters of reference designate corresponding parts throughout the several views.

Referring to the drawings, more particularly Figs. 1 to 4, 11 and 12 designate the conductors which are adapted to be looped, as shown, through the insulator, the latter being preferably constructed in the form of a parallelepiped in which two pairs of suitable longitudinal guide grooves 13 and 14 respectively are provided in the surface

thereof for said conductors as well as holes 15 and 16 extending therethrough at right angles to the conductor grooves. The grooves are constructed to slope from substantially the middle of the insulator toward each end to more positively insure the shedding of rain and moisture. The amount of insulating material included between the holes 15 and 16 is sufficient to provide the necessary mechanical strength to resist the compressive forces set up when the conductors are in service and placed under stress.

In order to provide ample creepage surface between the two conductors, raised barriers 17 and 18 are constructed to follow the respective pairs of grooves 13 and 14 from the corresponding ends of the insulator longitudinally inwardly to the holes 15 and 16 therethrough. This, together with the additional surface hereinafter described, will afford sufficient creepage surface laterally between the conductors to prevent "flashover" even during a rain or a sleet storm. The angle of inclination of grooves 13 and 14 so outwardly and inwardly from the middle of the insulator, furthermore, will serve to cause the insulator to shed rain or moisture and is such, also, as to follow the natural bight of the conductors, thus minimizing stress from this source.

In order to equalize the creepage surface over the ends of the insulator as well as over the sides thereof, a barrier or ridge 20 is constructed to extend along the entire outer rim of the insulator except at the ends where the conductors leave the said insulator. By suitably proportioning this barrier, the distance between the two conductors may be made the same at all points, or at least sufficiently great to prevent "flashover" at the voltages for which the insulator is designed. Suitable grooves or channels 21 and 22 are formed between the central barriers 17 and 18 respectively and barrier or ridge 20; and these grooves will further assist in shedding rain or moisture, being suitably pitched for this purpose.

In the modification illustrated in Figs. 5 to 7 and which show an insulator more particularly designed for higher voltages, the central barriers 20 and 21 surrounding the respective conductors do not terminate at the respective holes 22 and 23, but are continued entirely around the same to thereby increase the end creepage surface. Furthermore, additional holes 24 and 25, preferably

tapered inwardly from the outer surfaces, are provided through the insulator beyond the turn of the said barriers 30 and 31 and in substantially the planes of the respective 5 conductors. The grooves 36 and 37, which are formed between the central barriers 30, 31 and the outer barrier or ridge 38 are pitched not only outwardly substantially 10 from the middle of the insulator but also inwardly toward the holes 34 and 35. This affords a natural shedding surface for rain or moisture which will, therefore, drain through the said holes notwithstanding any 15 position in which the insulator may be placed.

I claim:—

1. A strain insulator adapted to receive two interlocking conductors at right angles to each other, said insulator being provided 20 with two barriers following each conductor, and a barrier following substantially the edge of the insulator except at the ends thereof at which the said conductors leave the same.
2. A strain insulator adapted to receive two interlocking conductors at right angles to each other, said insulator being provided with central barriers extending parallel to the said conductors upon either side thereof, and further barriers extending parallel 30 to said first-named barriers at either side thereof and transversely thereto beyond the inner ends of said barriers.
3. A strain insulator adapted to receive two interlocking conductors at right angles to each other, said insulator being provided with two barriers following each conductor and continued around the same, and a barrier following substantially the edge of the 40 insulator except at the ends thereof at which the said conductors leave the same.
4. A strain insulator adapted to receive two interlocking conductors at right angles to each other, said insulator being provided 45 with two barriers following each conductor and continued around the same, and a barrier following substantially the edge of the insulator except at the ends thereof at which the said conductors leave the same, said insulator being further provided with a drain hole between the inner end of each of the

central barriers and the corresponding transverse barrier.

5. A strain insulator adapted to receive two interlocking conductors at right angles 55 to each other, said insulator being provided with central barriers extending parallel to the said conductors upon either side thereof, and further barriers extending parallel to said first-named barriers at either side 60 thereof and transversely thereto beyond the inner ends of said barriers, the grooves formed between the said central barriers and the said additional barriers sloping substantially 65 from the middle of the insulator outwardly and inwardly.

6. A strain insulator adapted to receive two interlocking conductors at right angles to each other, said insulator being provided with two barriers following each conductor 70 and continued around the same, and a barrier following substantially the edge of the insulator except at the ends thereof at which the said conductors leave the same, said insulator being further provided with a drain 75 hole between the inner end of each of the central barriers and the corresponding transverse barrier and the grooves formed between the said central barriers and the said additional barriers sloping substantially 80 from the middle of the insulator outwardly to the open end of the insulator and inwardly toward the said drain openings at the closed ends.

7. A strain insulator adapted to receive 85 two interlocking conductors at right angles to each other, said insulator being provided with guide grooves in its surface and with holes through the said insulator to receive the bight of the respective conductors, said 90 guide grooves and holes being located substantially at right angles to each other, the said insulator being further provided with two barriers following each conductor, and a barrier following substantially the edge 95 of the insulator except at the ends thereof at which the said conductors leave the same.

Signed at New York, in the county of New York, and State of New York, this 18th day of March, A. D. 1915.

THOMAS SCULLY.
